**BATTERY JUMPER CABLE ASSEMBLY
WITH INTEGRAL LIGHT**

Allan M. Coleman, Highland Park, Ill., and Carl J. Hawkins and Raymond J. Abair, Toledo, Ohio, assignors to Coleman Cable & Wire Company, River Grove, Ill.

Filed July 12, 1971, Ser. No. 161,391

Term of patent 14 years

Int. Cl. D13—03

U.S. Cl. D26—1

FIG.1

FIG.2

FIG.3

FIG.4

FIG.5

FIG. 1 is a perspective view of the battery jumper cable assembly with integral light, the cable portion being shown coiled.

FIG. 2 is a front elevational view of the integral light portion of the assembly.

FIG. 3 is a side elevational view of the integral light portion of the assembly, the opposite side being identical.

FIG. 4 is a top plan view of the integral light portion of the assembly, the bottom being identical to the top.

FIG. 5 is a rear elevational view of the integral light portion of the assembly.

Broken line showing of clamps in FIG. 1 is for illustrative purposes only.

We claim:

The ornamental design for a battery jumper cable assembly with integral light, substantially as shown and described.
